US00D995758S

(12) **United States Design Patent** (10) **Patent No.:** **US D995,758 S**
(45) **Date of Patent:** **** Aug. 15, 2023**

(54) **TUBE ASSEMBLY AND CONNECTOR**

(71) Applicant: **Fisher & Paykel Healthcare Limited**,
Auckland (NZ)

(72) Inventors: **Gareth Thomas McDermott**, Auckland (NZ); **Jaiden Gray Walmsley**, Auckland (NZ); **Craig Karl White**, Auckland (NZ); **Alicia Jerram Hunter Evans**, Auckland (NZ)

(73) Assignee: **Fisher & Paykel Healthcare Limited**,
Auckland (NZ)

(**) Term: **15 Years**

(21) Appl. No.: **29/788,503**

(22) Filed: **Jun. 11, 2021**

(51) LOC (14) Cl. **29-02**

(52) U.S. Cl.

USPC **D24/110.4**

(58) **Field of Classification Search**

USPC D24/110.4, 110.5, 110, 112, 127, 128,
D24/129, 108

CPC A61M 16/0465; A61M 16/0427; A61M
16/0488; A61M 16/0434; A61M 1/84

(57) **CLAIM**

The ornamental design for a tube assembly and connector, as shown and described.

DESCRIPTION

FIG. 1 is a front, right side and top perspective view of a tube assembly showing our new design.

FIG. 2 is a rear, left side and top perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof, enlarged for clarity; and,

FIG. 8 is a rear view thereof, enlarged for clarity.

The appearance of the tube between the break lines form no part of the claimed design.

1 Claim, 7 Drawing Sheets
